UNITED STATES PATENT OFFICE.

HAROLD F. BARTLEY, OF NEW YORK, N. Y.

HAIRPIN.

Application filed October 6, 1927. Serial No. 224,303.

The invention relates to a new and improved hairpin especially adapted for use in bobbed hair, although it may of course be used for securing hair of any character or 5 length.

Bobbed hair in practically all of the present styles is so short that ordinary hairpins are not adequately retained by it and the use of such hairpins is therefore annoying, 10 if not entirely impractical.

My invention consists in a hairpin in the general form of a spiral or convolute, including portions designed to definitely and resiliently grip short or long hair and retain 15 it in predetermined position, and at the same time retain the pin firmly in engagement with the hair, the device being preferably designed for application by a rotary movement.

20 Preferably also the device is made in the form of a symmetrical, double-convolute and in substantially dished form as later explained in detail. As otherwise described, the device is substantially a double hairpin 25 arranged in spiral or screw form for application by rotary motion, each part of the double pin including closely-spaced resilient portions which grip the hair near the roots, and inner, larger or open portions in which 30 larger bunches of hair are located in such manner that they lie flat or in normal position, these inner portions being also designed to prevent inadvertent reverse movement or displacement of the pin.

35 The characteristics and advantages of the invention are further sufficiently explained in connection with the following detail description of the accompanying drawings, which illustrate certain representative em- 40 bodiments. After considering these examples, skilled persons will understand that many variations may be made without departing from the principles involved, and I contemplate the employment of any struc- 45 tures that are properly within the scope of the appended claims.

Fig. 1 is a plan view of a hairpin embodying the invention in one form.

Fig. 2 is a side elevation.

50 Fig. 3 shows one of the pins in use.

Fig. 4 is a side elevation of a modification.

The hairpin is preferably formed from a single piece of any suitable material, usually yieldable and preferably resilient, such 55 as wire, celluloid, bone or any other material commonly used for hairpins. When

wire or like corrodible material is employed, it is usually coated with a protecting material. In the present specific example the pin consists of a single piece of spring wire bent into the general form of a symmetrical, double spiral or convolute and including a central transverse member 1 which serves as a handle, the convolutes or spirals 2 extending from opposite ends thereof. The device is 60 preferably of generally dished formation as best shown in Fig. 2; or it may be described as a double conical convolute with each of the portions 2 curving in a generally spiral manner about the center of the handle member 1, and each also being deflected in the same direction away from the plane of said handle member. The end 3 of each member 2 is preferably additionally bent downwardly and slightly outwardly to provide an end 65 or point which will easily enter the hair and then by rotary movement of the pin, grasped by the handle part 1, hair is forced into the zones or spaces 4 between the adjacent parts of the two convolutes, with a screw or wedg- 70 ing action whereby the pin is firmly secured in position and correspondingly securely holds the gripped hair in the position intended. While the spacing of the turns may vary considerably, it is usually preferable 75 to arrange the adjacent portions of the two convolutes quite close together, so that when a lock of hair is forced between them by the wedging action of the flared end portions 3, 80 these adjacent portions of the convolutes will 85 resiliently and tightly grip the hair near 90 the roots. The inward portions of the convolutes in cooperation with the central cross member, provide two enlarged hair-receiving 95 spaces 5 in which, after application of the pin in the manner just stated, relatively 100 large bunches or locks of hair are accommodated, these spaces being of sufficient size to permit the hair to lie in a flat or other natural position, while at the same time the closely adjacent portions of the convolutes grip other hairs near the roots, to firmly retain the device in position close to the scalp, so that when properly applied practically no part of the hairpin is exposed or visible ex- 105 cepting possibly the central cross piece or handle portion 1. The location of relatively large bunches or locks in the spaces 5 usually conceals the cross piece 1 and also serves effectively to prevent inadvertent reverse ro- 110 tation or other displacement of the pin, since it is evident that any such tendency is resist-

ed by the practical impossibility of the larger bunches escaping from the spaces 5 through the narrower passages at 6 leading to the adjacent portions of the two convolutes.

5 From the preceding description it will now be understood that the device is, in one sense, a double hairpin, arranged in spiral or screw form, each of such double pins comprising a part of the central member and one of the 10 convolutes, these double pins acting cooperatively to firmly retain the hair and to firmly retain the device itself in position in the manner previously described.

Fig. 3 sufficiently explains one mode of 15 use. The pin is shown holding a front lock in rearward position by first engaging the pin with the front lock, moving it back to the desired position and then engaging the pin with portions of the side hair, by rotary 20 movement of the pin as sufficiently explained above.

It is obvious that while the pin is securely 25 retained in position, when desired it may easily be removed manually by reverse rotation.

Fig. 4 shows a modification in which gripping portions 5 of the spirals or convolutes are waved or crimped to provide an amplified gripping action.

30 In either form of the device the length of the spiral portions 2 may evidently be varied considerably; that is these portions may be longer or shorter, without materially affecting the general structural principle and 35 mode of use.

I claim—

1. A hair pin of yieldable material comprising a central portion serving as the sole handle member and extending portions disposed on opposite sides of said central portion, said extending portions being arcuate and substantially parallel to one another but spaced from one another to provide hair receiving spaces between said extending portions, said extending portions terminating in free ends respectively spaced from one another and from said substantially parallel portions, said extending portions and said free ends thereof being dished relative to one 50 another.

2. A hair pin formed of longitudinally extending material, the opposite portions of which are bent arcuately and downwardly and substantially parallel to one another but 55 spaced from one another to provide hair receiving spaces between said arcuately bent portions, the portion of said material interconnecting the arcuately bent portions serv-

ing as the sole handle portion of the hair pin, 60 said arcuately bent portions being dished relative to one another and terminating in oppositely disposed free ends extending arcuately from opposing locations in the same direction.

3. A hair pin formed of longitudinally extending material, the opposite portions of which are bent arcuately and downwardly and substantially parallel to one another but spaced from one another to provide hair receiving spaces between said arcuately bent 70 portions, the portion of said material interconnecting the arcuately bent portions being disposed in a plane and serving as the sole handle portion of the hair pin, said arcuately bent portions being dished relative to 75 one another and terminating in oppositely disposed free ends extending arcuately from opposing locations in the same direction, said free ends flaring downwardly and outwardly relative to said arcuately bent portions.

4. A hair pin formed of longitudinally extending material, the opposite portions of which are bent arcuately and downwardly and substantially parallel to one another but 85 spaced from one another to provide hair receiving spaces between said arcuately bent portions, said arcuately bent portions being crimped, the portion of said material interconnecting the arcuately bent portion serving 90 as the sole handle portion of the hair pin, said arcuately bent portions being dished relative to one another and terminating in free 95 ends extending from opposite locations arcuately in the same direction.

5. A hair pin formed of longitudinally extending material, the opposite portions of which are bent arcuately and downwardly and substantially parallel to one another but spaced from one another to provide hair receiving spaces between said arcuately bent 100 portions, said arcuately bent portions being crimped, the portion of said material interconnecting the arcuately bent portion being substantially rectilinear and serving as the 105 sole handle portions of the hair pin, said arcuately bent portions being dished relative to one another and terminating in free ends extending from opposite locations arcuately in the same direction, said free ends flaring 110 downwardly and outwardly relative to said arcuately bent portions.

In testimony whereof I have signed this specification this 1st day of October, 1927.

HAROLD F. BARTLEY.
